SHAVING MACHINE FOR CYLINDRICAL SOUND RECORDS

Filed May 15, 1929. 2 Sheets-Sheet 2

UNITED STATES PATENT OFFICE

BRUNO E. JACOB, OF RIPON, WISCONSIN

SHAVING MACHINE FOR CYLINDRICAL SOUND RECORDS

Application filed May 15, 1929. Serial No. 363,257.

The present invention is directed to improvements in shaving machines for cylindrical sound records.

The primary object of the invention is to provide a device of this character wherein the shaving blade will be automatically set to shave each cylinder to the proper depth.

Another object of the invention is to provide a device of this character so constructed that after the shaving blade has moved the entire length of the cylinder the blade will be automatically shifted in order that the successive shaving operation will cut the cylinder deeper.

Another object of the invention is to provide a device of this character which can be easily and quickly applied to shaving machines of well known construction.

With these and other objects in view, this invention resides in the novel features of construction, formation, combination and arrangement of parts to the hereinafter more fully described, claimed and illustrated in the accompanying drawings, in which:

Figure 1 is a plan view of a conventional form of shaving machine, showing the device applied thereto.

Figure 2 is a sectional view on the line 2—2 of Figure 1.

Figure 3 is a sectional view on the line 3—3 of Figure 2.

Referring to the drawings, 1 designates the top of a conventional cabinet in which is contained the conventional form of driving mechanism, and upon this top is mounted the usual screw feed shaft 2 which serves to move the carriage 3 longitudinally upon the guide rod 4. The carriage 3 carries the shaving blade 5 and the customary shavings discharge chute 6.

The mandrel 7 shows mounted thereon the usual sound cylinder 8 which is engaged by the blade 5 during the shaving operation. The blade 5 is carried by the holder 8' which is slidable in the sleeve 9 which, as usual, forms a part of the carriage 3. The holder has its rear end protruding from the sleeve and carries a depending plate 10 which is adapted to support the feed screw 11, the spring 10' serving, as is customary, to urge

the holder rearwardly. In order to adjust the screw 11, a wheel 12 is fixed thereto in lieu of the usual thumb wheel, it being obvious that when the wheel 12 is rotated the holder 8 will be moved forwardly. The wheel 12 is provided with peripheral teeth 13 so cut as to provide thirty notches 14. The front face of the wheel 12 is provided with radial lines 15, ten of which are employed, said lines being preferably colored red and numbered successively from 1 to 10. The three notches between any pair of lines 15 vary in size. For instance, the notches A are of greater area than the notches B, while the notches C are of less area than the notches B, the purpose of which will be later explained.

A bowed resilient trip bar 15 is provided and has one end fixed to the top 1 of the cabinet, the free terminal 16 thereof being elevated and held against upward movement by the set screw 17 carried by the bracket 18, also mounted upon the top 1. It will be observed upon reference to Figure 3 that the terminal 16 of the trip bar is in the path of movement of the wheel 12 so that when the carriage 3 moves to the right to its fullest extent the terminal 16 will engage in one of the notches to rotate the wheel a sufficient distance to operate the feed screw 11, whereupon the blade holder will be moved to extend the blade to act upon the cylinder.

The carriage 3 carries the usual arm 19 to hold the blade engaged with the cylinder and serves to elevate the carriage in order that the blade 5 may be lifted after each shaving operation. Obviously, the elevation of the arm lifts the half feed nut 20 from the feed screw 2 to permit movement of the carriage so that the cylinders can be applied or removed from the mandrel 7. A pointer 21 is mounted upon the carriage 3 and cooperates with the numbers upon the wheel 12 in order that the wheel can be set properly for the various shaving operations.

Briefly, the operation is as follows:

The wheel 12 being properly set, the carriage 3 moves from the right, or in the direction of the arrow, and just before it reaches its extreme right position, the terminal 16 engages a notch C, thus turning the wheel 12

a distance of one notch so that the holder 8 will be shifted in order that the blade 5 will cut to a deeper depth. Thus, the operator need not manually adjust the blade as is now customary. Just before the carriage moves to extreme right position the terminal 16 has engaged a notch C and continued movement of the carriage causes the wheel 12 to be rotated the distance covered by the notch B, thus adjusting the blade to shave to a slightly greater depth. The carriage is now returned to its left hand position for the second shaving operation and when it has just about completed its fullest travel to the right, the terminal 16 engages the notch A, rotating the wheel the distance of the notch C. Since the notches C include a smaller arc of the periphery of the wheel 12 than the notches B, the distance the wheel 12 is rotated is less, and consequently the shaving cut will be of less depth.

The carriage is then again returned to the left and a third cut made. At this time the notch B rotates the wheel 12 the distance covered by notch A, the largest of the three, preparatory to making the first cut on the cylinder next to be shaved. The depth of the cut made by the blade varies and since each cylinder is shaved three times, the first cut should be the deepest, the second less, and the third still less. The wheel 12 may have a knob 22 fixed thereto operable to adjust the wheel previous to the first cutting or shaving operation.

35 What is claimed is:

A machine for shaving cylindrical sound records comprising a cylinder receiving mandrel, a screw feed shaft geared to the mandrel, a carriage detachably connected with the screw feed shaft, a blade holder on the carriage, a screw, connecting means between the screw and blade holder, a knob on the screw for manual adjustment thereof, a wheel fixed to the screw and provided with groups of teeth of different size and having a scale to facilitate selection of the desired group of teeth, a trip in the path of the toothed wheel, and means for adjusting the trip to vary the period of action on the selected group of teeth.

In testimony whereof I affix my signature.

BRUNO E. JACOB. [L.S.]
